UNITED STATES PATENT OFFICE.

STANLEY EMBOR, OF CHICAGO HEIGHTS, ILLINOIS.

SAFETY DEVICE FOR RIVETING HAMMERS.

Application filed February 21, 1924. Serial No. 694,430.

This invention relates to improvements in attachments for riveting hammers and more particularly to an improved coupling means for attaching a riveting hammer, or rivet buster to the holder thereof.

The primary object of the invention is to provide an improved means for holding the rivet set in position in the holder in a manner that will permit the rivet set to be quickly released when desired, but which will firmly maintain the rivet set in position while it is in use, and prevent the operator thereof from being injured.

Another object of the invention is to provide a device of this character which may be easily manipulated to permit the hammer to be removed from the holder when desired.

Other objects of the invention will appear upon consideration of the following detail description and accompanying drawings, wherein:

Figure 1 is a longitudinal section through the device constructed in accordance with my invention, showing a riveting hammer mounted in operative position.

Figure 2 is a similar view showing the rivet set being withdrawn, the locking means being released,

Figure 3 is a perspective view of one of the locking elements,

Figure 4 is a transverse section taken on the line 4—4 of Figure 1,

Figure 5 is a similar view taken on the line 5—5 of Figure 2,

Figure 6 is a plan view of the end of the holder showing one of the locking pawls in position and retaining collar removed.

Referring to the drawing by numerals, the body 1 of the hammer is provided with a cylindrical end as shown having a central longitudinal bore 2 which is adapted to receive the tool 3 comprising the shank 4 and head 5. The bore is adapted to snugly fit the shank 4 but in a manner so that the latter may be moved into and out of engagement therewith when the tool is arranged in or out of position, as the case may be.

The shank 4 is provided with diametri-

cally opposite slots adapted to receive locking pawls 7 which are equipped with lugs 8 adapted to fit slots 6 formed in the shank 4 when it is thrust into the bore 2. The locking pawls 7 are arranged in recesses 9 in the body 1 at diametrically opposite sides thereof, and the recesses 9 are shaped and of sufficient size to permit inward and outward movement of the locking pawls 7.

Surrounding the body 1 is a sleeve 10 adapted to be rotated and, as shown in Figs. 4 and 5, the sleeve is provided with a longitudinal opening which is substantially elliptical in cross section, the major diameter of the ellipse being large enough to permit the locking pawls 7 to move outwardly and thus disengage the slot 5 in the shank 4, whereas the minor axis of the ellipse is small enough to cause the sides of the ellipse at this point to engage the pawls and force the lugs 8 into the slots 6 whereby the shank will be held in operative position as shown in Fig. 1. To lock the sleeve 10 in operative position, a locking pin 11 is provided which is pressed by a spring 12 whereby the end of the pin will engage an opening or recess 13 in the retaining collar 14 which is screw threadedly mounted upon the end of the body 1 after the sleeve 10 has been placed in position.

By giving a quarter turn to the sleeve 10 as indicated in Figs. 4 and 5 of the drawing the pawls will be readily released or engaged as desired for releasing or retaining the tool in position in the holder. In this manner any interchange of different types of tools may be made and the latter will be effectively held in operative position while the implement is in use.

What is claimed is:

In combination with a tool having a cylindrical shank provided at diametrically opposite sides with longitudinally disposed slots, a holder comprising a cylinder, a sleeve positioned on said cylinder for turning movement, said sleeve having one end portion of the opening therein elliptical in transverse section, a collar threaded upon one end of said cylinder for retaining the sleeve thereon, a locking pin slidably

mounted in the sleeve and engageable with the collar for holding said sleeve against turning movement, said cylinder having slots formed therein, locking pawls arranged in said slots of said cylinder and held against the sides of the shank of the tool, and laterally disposed lugs on said pawls adapted to enter the slots in the shank of the tool when the shorter diameter of

the elliptical opening in the sleeve is disposed transversely of said lugs, the said lugs being adapted to swing out of the slots in the tool when the longitudinal diameter of the elliptical opening in the sleeve is disposed transversely of the lugs.

In testimony whereof, I have affixed my signature.

STANLEY EMBOR.
